(57) **CLAIM**

The ornamental design for a vacuum container with lid and strainer, as shown and described.

DESCRIPTION

FIG. 1 is an isometric view of a vacuum container with lid and strainer showing my new design;

FIG. 2 is a left side elevation view thereof;

FIG. 3 is a front elevation view thereof, with the rear elevation view a mirror image thereof;

FIG. 4 is a right side view thereof;

FIG. 5 is a bottom view thereof;

FIG. 6 is a top plan view thereof;

FIG. 7 is a side view thereof;

FIG. 8 is cross sectional view taken along lines 8-8 of FIG. 7; and,

FIG. 9 is an exploded view illustrating the internal makeup thereof.
